[57] CLAIM

The ornamental design for an element of a shoe upper, as shown and described.

DESCRIPTION

FIG. 1 is a side elevational view of a side element of a shoe upper showing our new design applied to one side of a shoe;

FIG. 2 is a side elevational view of the element applied to the opposite side of the shoe;

FIG. 3 is a side elevational view of an alternate embodiment of our new design applied to one side of a shoe; and,

FIG. 4 is a side elevational view of the alternate embodiment applied to the opposite side of a shoe.

The broken line showing of a shoe in the figures is environmental only and forms no part of the claimed design.
